UNITED STATES PATENT OFFICE.

HARRISON D. FLEGEL, OF RACINE, WISCONSIN, ASSIGNOR TO ARNOLD ELECTRIC COMPANY, OF RACINE, WISCONSIN, A CORPORATION OF WISCONSIN.

DISPENSER.

Application filed May 6, 1926. Serial No 107,071.

My invention relates to dispensers and has a number of objects and advantages in view.

The dispenser of my invention is of particular service in delivering measured quantities of malted milk in dry form, although it is not to be limited to such use.

A dispenser constructed in accordance with one embodiment of my invention includes a container having a horizontal bottom wall formed with an upright discharge opening therethrough, a horizontal closure plate for said opening located below and engaging the container bottom, a horizontal measuring wheel above and in close proximity to the closure bottom and having teeth defining a succession of pockets communicable, in sequence, with the interior of the container and the discharge opening, and mechanism coupling said measuring wheel and closure and having one portion connected with and serving to move the measuring wheel horizontally in a uniform direction and another portion connected with said closure and serving to move this closure horizontally in an opening direction as each filled pocket is moved into register with said discharge opening and to thereafter move the closure in a closing direction. A dispenser thus constructed has its delivering mechanism and the closure for its discharge opening very compactly arranged so that the length of travel of any measured quantity of its contents undergoing discharge is reduced to a minimum within the structure of the dispenser, a characteristic which is especially important in dispensing malted milk which so readily absorbs moisture from the external air.

In accordance with another feature of my invention, a swinging arm is coupled with the plate to turn it to its opened and closed positions. This arm is upwardly spring-pressed against the plate and there is a connection between the plate and arm that is in register with the discharge opening when the plate is closed and which connection is formed to permit universal swinging movement of the plate with reference to the arm to enable the plate to have full engagement with the margin of the discharge opening so that the opening is thoroughly sealed against the admission of moisture when the plate is in closed position. To prevent any of the container contents from adhering to the bottom of the container in the region of

the discharge opening, I form the bottom of the container with a wall portion that margins the opening and which is downwardly tapered upon its outer side. I provide means for varying the measured quantity undergoing discharge, this means residing in a plate overlying and spaced vertically apart from the teeth and carrying a portion extending toward the teeth cooperating therewith to effect one measurement of the material being discharged and movable away from the plane of rotary movement of the teeth to effect another measurement.

I will explain my invention more fully by reference to the accompanying drawings in which Fig. 1 is a side view of a dispenser as I preferably construct it; Fig. 2 is a plan view of the base portion of the dispenser, the displaceable part of the container being removed; Fig. 3 is a sectional view on line 3—3 of Fig. 2, the lower part of the displaceable part of the container being also illustrated in this figure; Fig. 4 is a sectional view on line 4—4 of Fig. 5; Fig. 5 is a bottom view of the dispenser as it appears when removed from the supporting base that is shown in Fig. 1; Fig. 6 is a perspective view of a part of the structure; Fig. 7 is a perspective view of the closure plate for the discharge opening and a portion of the operating arm therefor; Fig. 8 is a sectional view on line 8—8 of Fig. 5; and Fig. 9 is a perspective view of a portion of the structure which supports the removable container.

The upright cylindrical container 1 has a discharge opening 2 in its bottom wall 3. This opening has a closure in the form of an arcuate horizontal spring plate 4 carried on the exterior of the container upon an arm 5 through the intermediation of a pin 6 desirably carried by the plate 4, the lower end of the pin being rounded, and there received in a socket 7 formed in the top side of the arm. The plate has stirrups 4' that embrace the arm whereby the arm may move the plate. The arm is pressed upwardly against the pin by means of a coiled spring 8 which presses upwardly against the arm. This spring desirably surrounds the shaft 5' being bottomed upon a washer 5² that is held in place by a nut 5³.

A flat horizontal measuring wheel 9 is journaled upon the shaft 5'. This wheel is formed with teeth 10, preferably in the form of blades, which define a circular succession

of pockets 11 adapted to be successively placed in register with the discharge opening. This wheel is within the container and turns upon the bottom wall thereof, the 5 teeth ends closely approaching the cylindrical wall of the container in order that the quantities in the pockets may be accurately measured in conjunction with a levelling arcuate plate 12 carried by and with- 10 in the container above and in register with the discharge opening and pressing upon the top of the wheel. This plate constitutes a closure for the receiving end of the particular pocket 11 that is placed in register 15 with the discharge opening, and is of limited extent to permit communication between the remaining pockets and the interior of the container in order that they may be filled. The plate 12 also agitates the material within the container, a function which is supplemented by the agitator bar 13 mounted to turn with the wheel. This bar is desirably continued upon both sides of the shaft 5'. 20

25 The plate 12 is formed with a depending wing portion 12' attached thereto by means of a screw 12''. This portion extends toward the teeth or blades 10 which are vertically spaced apart from the plate 12 itself, and 30 serves to reduce the height of the measured quantity of material to the height of the blades. When the portion 12' is removed, it permits larger quantities of material to remain between the blades for discharge 35 through the discharge opening 2. The plate 12 is positioned, at its inner end, by the shaft 5' whose upper end passes through a hole in an extension of the plate. There is also a lug 12''' formed upon the plate, at its 40 outer edge, which is received in a notch 12'' in the shoulder 12'' in the base portion of the container. The cylindrical portion of container 1 that is above the wheel rests upon the shoulder 12''' and holds the lug 12''' in the notch. 45

In the preferred embodiment of the invention, the shaft 5' is turned in a uniform direction and is connected with the wheel to turn it in a like direction. The shaft has 50 a head 14 fixed thereon and received in a recess in the bottom of the wheel. The upper end of the shaft is polygonal and enters a correspondingly shaped opening in the wheel to couple the wheel and shaft. 55 Mechanism is employed to rotate the wheel step by step, each movement of the wheel withdrawing the pocket last emptied from the discharge opening and placing an ensuing and filled pocket in register with this 60 opening. This step by step mechanism includes a ratchet wheel 15 secured upon the lower end of the shaft 5'. This ratchet wheel 15 is turned step by step to turn the measuring wheel step by step by means of 65 the actuating spring pressed pawl 16 car- 70 ried by the continuation 17 of the arm 5. Another continuation 18 of the arm 5 is provided with a handle bar 19 whereby the unitary structure 5, 17, 18 may be turned against the force of a spring 20 which is so connected with the member 5, 17, 18 as to resist manual movement thereof in a direction that operates the ratchet 15. A lug 21 upon the bottom of the container defines the resting position of said member. A thumb 75 rest 22 is provided upon the container to facilitate the operation of the aforesaid member. Whenever this member is sufficiently turned against the force of the spring 20, the measuring wheel is moved one inter-tooth space to bring another measured quantity of material into register with the discharge opening. The arm 5, at the same time, moves the closure plate from beneath the discharge opening so that material may 80 be discharged from the pocket newly positioned in register with the discharge opening. When the handle bar 19 is released, the spring 20 will retract the member 5, 17, 18 to bring the plate 4 into closed position but without causing a reverse movement of the wheel, the pawl 16 escaping this wheel during the closing movement of the plate 4. The wheel is held from any backlash movement by means of a roller 23 which is spring pressed into an inter-tooth space of the wheel preferably by means of the spring 20, in which case this spring functions 85 through an arm 24 pivoted at one end and carrying the roller at the other end. 90

95 Three sides of the discharge opening are margined by a wall which is downwardly tapered upon its outer side by which malted milk or other dry material is prevented from caking upon the bottom of the container and around said opening. When such a wall formation is employed, I desirably provide a levelling post 25 along side of the opening that is engaged by the plate 4 when in open position so that the plate cannot tilt out of 100 its normal horizontal plane. 11

The projection 26, shown in Fig. 2, may consist of any means adapted to the support upon the interior wall of the container and projecting into the path of the resilient 111 blades 10. 11

The operation of my dispenser is as follows: 112

The thumb, having been placed upon the thumb piece 22, and the fingers engaging the handle 19, the lever 18 may be actuated to the left in Fig. 1, the pawl 16 (Fig. 5) engages one of the shoulders on the wheel 15 and rotates the wheel 15. The lever 24, with its friction roller 23, is resiliently held between pairs of shoulders on the wheel 15, and on actuation of the lever 18, the spring tension of the spring 20, extending between the lever 18 and the lever 24, is increased, but 120 the motion of the wheel 15 cams the roller 125 130

23 from position between the shoulders to a position upon one of the projections of the wheel 15, after which the spring 20 forces the roller 23 into the next notch on the wheel 15, causing said wheel with the associated discharge mechanism to move with a snap to its final position.

During the motion of the hub 9 with the resilient blades 10, the blades 10 engage the projection 26 situated adjacent the discharge opening, and after being rearwardly sprung by the said projection, the blades pass over it, each blade being placed in vibration before it reaches the discharge opening. In order to facilitate free vibration of the blades 10, it will be noted that they are disposed in close proximity to the bottom of the container but out of contact therewith, as well as being out of contact with the covering plate 12.

Changes may be made without departing from the invention.

Having thus described my invention, I claim:—

1. In a dispenser, a container having a bottom with an extending bearing post, said bottom having a discharge aperture therein, measuring and discharging mechanism in said container comprising a cylindrical hub journaled upon said post, and a plurality of resilient partitions extending radially from said hub.

2. In a dispenser, the combination with a container having a horizontal bottom wall formed with an upright discharge opening therethrough; of a horizontal closure plate for said opening located below and engaging the closure bottom; and a swinging arm with which said plate is coupled to turn therewith and upon which plate said arm is upwardly spring pressed, said plate and arm having pin and socket connection in register with the discharge opening when the plate is closed and formed to permit universal swinging movement of the plate with reference to the arm to enable the plate to have full engagement with the margin of said opening.

3. In a dispenser, the combination with a container having a horizontal bottom wall formed with an upright discharge opening therethrough; of a horizontal closure plate for said opening located below and engaging the closure bottom; and a swinging arm with which said plate is coupled to turn therewith, there being a connection between said plate and arm in register with the discharge opening when the plate is closed and formed to permit universal swinging movement of the plate with reference to the arm to enable the plate to have full engagement with the margin of said opening.

4. In a dispenser, the combination with a container having a horizontal bottom wall formed with an upright discharge opening

therethrough; of a horizontal closure plate, for said opening located below and engaging the closure bottom which is formed with a wall portion margining said opening and which is downwardly tapered upon its outer side.

5. In a dispenser, a container having a bottom with an extending bearing post, said bottom having a discharge aperture therein, measuring and discharging mechanism in said container comprising a cylindrical hub journaled upon said post, and a plurality of resilient partitions extending radially from said hub, said partitions being of less height than the thickness of said hub.

6. In a dispenser, the combination with a container having a horizontal bottom wall formed with an upright discharge opening therethrough; of a horizontal closure plate for said opening located below and engaging the closure bottom; and a swinging arm with which said plate is coupled to turn therewith and upon which plate said arm is upwardly spring-pressed.

7. In a dispenser, a container having a bottom with an extending bearing post, said bottom having a discharge aperture therein, measuring and discharging mechanism in said container comprising a cylindrical hub journaled upon said post, a plurality of resilient partitions extending radially from said hub, said partitions being of less height than the thickness of said hub, and means for leveling the charge between said partitions comprising a wall extending below said hub.

8. In a dispenser, a container having a bottom with an extending bearing post, said bottom having a discharge aperture therein, measuring and discharging mechanism in said container comprising a cylindrical hub journaled upon said post, a plurality of resilient partitions extending radially from said hub, said partitions being of less height than the thickness of said hub, and an actuating shaft extending through said bearing post supporting said hub and partitions, out of contact but in close proximity to said bottom.

9. In a dispenser, a container having a bottom with an extending bearing post, said bottom having a discharge aperture therein, measuring and discharging mechanism in said container comprising a cylindrical hub journaled upon said post, a plurality of resilient partitions extending radially from said hub, said partitions being of less height than the thickness of said hub, and an actuating shaft extending through said bearing post supporting said hub and partitions, out of contact but in close proximity to said bottom, said shaft having a non-circular portion engaging a similar aperture in said hub to key said shaft and hub together.

10. In a dispenser, a container having a

- bottom with an extending bearing post, said bottom having a discharge aperture therein, measuring and discharging mechanism in said container comprising a cylindrical hub 5 journaled upon said post, a plurality of resilient partitions extending radially from said hub, said partitions being of less height than the thickness of said hub, an actuating shaft extending through said bearing post 10 supporting said hub and partitions, out of contact but in close proximity to said bottom, and a shield plate of substantially larger area than the top area of the chamber between said partitions, having a downwardly 15 projecting flange for leveling the charge between said partitions, and locked to shield said chambers from filling when in discharging position.
11. In a dispenser, a container having a 20 bottom with an extending bearing post, said bottom having a discharge aperture therein, measuring and discharging mechanism in said container comprising a cylindrical hub journaled upon said post, a plurality of resilient partitions extending radially from said hub, said partitions being of less height than the thickness of said hub, and an actuating shaft extending through said bearing post 25 supporting said hub and partitions, out of contact but in close proximity to said bottom, said container having an annular shoulder above said partitions to support a second container, said shoulder being shaped to receive and support a shield plate flush 30 with its upper edge.
12. In a dispenser, a container having a bottom with an extending bearing post, said bottom having a discharge aperture therein, measuring and discharging mechanism in 40 said container comprising a cylindrical hub journaled upon said post, a plurality of resilient partitions extending radially from said hub, said partitions being of less height than the thickness of said hub, an actuating shaft extending through said bearing post 45 supporting said hub and partitions, out of contact but in close proximity to said bottom, said container having an annular shoulder above said partitions to support a second container, said shoulder being shaped to receive and support a shield plate flush 50 with its upper edge, and a shield plate of substantially larger area than that required to cover the chamber between two partitions supported by said shoulder, and having an aperture loosely receiving said shaft.
13. In a dispenser, a container having a 60 discharge aperture in its bottom and a seating surface bounding said aperture, a shaft journaled in said bottom and a lever supported on said shaft, said lever supporting for universal movement a sliding closure for said aperture.
14. In a dispenser, a container having a 65 discharge aperture in its bottom and a seat- ing surface bounding said aperture, a shaft journaled upon said post, a plurality of resilient partitions extending radially from said hub, said partitions being of less height than the thickness of said hub, an actuating shaft extending through said bearing post 70 supporting said hub and partitions, out of contact but in close proximity to said bottom, and a shield plate of substantially larger area than the top area of the chamber between said partitions, having a downwardly 75 projecting flange for leveling the charge between said partitions, and locked to shield said chambers from filling when in discharging position.
15. In a dispenser, a container having a discharge aperture in its bottom and a seating surface bounding said aperture, a shaft journaled in said bottom, a lever supported on said shaft, said lever supporting for universal movement a sliding closure for said aperture, and a plurality of stirrups on said lever limiting the universal movement of 80 said closure.
16. In a dispenser, a container having a discharge aperture in its bottom and a seating surface bounding said aperture, a shaft journaled in said bottom, a lever supported on said shaft, said lever supporting for universal movement a sliding closure for said aperture, a plurality of stirrups on said lever limiting the universal movement of said closure, and a projecting surface upon said bottom for engaging and supporting said closure when in open position.
17. In a dispenser, a container having a discharge aperture in its bottom and a seating surface bounding said aperture, a shaft journaled in said bottom, a lever supported on said shaft, said lever supporting for universal movement a sliding closure for said aperture, and a spring on said shaft to urge 90 said lever and closure against said seat.
18. In a dispenser, a container having a discharge aperture in its bottom and a seating surface bounding said aperture, a shaft journaled in said bottom, a lever supported on said shaft, said lever supporting for universal movement a sliding closure for said aperture, a spring on said shaft to urge said lever and closure against said seat, and a diametrical extension on said lever in sliding contact with said bottom to serve as a fulcrum for the sliding movement of said 100 lever on said shaft.
19. In a dispenser, a container having measuring and discharging mechanism within the same, a shaft journaled in a wall of said container to actuate said mechanism, a wheel having a plurality of shoulders, said wheel being fixed on said shaft, an actuating lever rotatively supported on said shaft and having a spring pawl to engage said shoulders, and a friction roller adapted to resiliently engage between pairs of said shoulders.
20. In a dispenser, a container having measuring and discharging mechanism within the same, a shaft journaled in a wall of 115 said container to actuate said mechanism, a wheel having a plurality of shoulders, said wheel being fixed on said shaft, an actuating lever rotatively supported on said shaft and having a pivoted cam lever engaging 120
- 130

between said shoulders, stop means for said actuating lever, and resilient means tensioned between said cam lever and said actuating lever.

- 5 21. In a dispenser, a container having measuring and discharging mechanism within the same, a shaft journaled in a wall of said container to actuate said mechanism, a wheel having a plurality of shoulders, said
10 wheel being fixed on said shaft, an actuating lever rotatively supported on said shaft

and having a pivoted cam lever engaging between said shoulders, stop means for said actuating lever, resilient means tensioned between said cam lever and said actuating lever, a transverse handle on said lever, and a thumb rest on said container to facilitate actuation of said lever. 15

In witness whereof, I hereunto subscribe my name.

HARRISON D. FLEGEL.
